FIG. 1

FIG. 2

FIG. 3

FIG. 1 is a perspective view of my design for a tire; it is to be understood that the detailed tread and sidewall design continues throughout the circumference of the tire, and that both sidewalls are the same.

FIG. 2 is a fragmentary perspective view.

FIG. 3 is a fragmentary top plan view.

I claim:

The ornamental design for a tire, as shown and described.
